H. H. CLARK

INTERRUPTER MECHANISM

Filed April 29, 1921

Fig. 1

Fig. 2

UNITED STATES PATENT OFFICE.

HAROLD H. CLARK, OF SPRINGFIELD, MASSACHUSETTS, ASSIGNOR TO WICO ELECTRIC COMPANY, OF SPRINGFIELD, MASSACHUSETTS, A CORPORATION OF MASSACHUSETTS.

INTERRUPTER MECHANISM.

Application filed April 29, 1921. Serial No. 465,537.

To all whom it may concern:

Be it known that I, HAROLD H. CLARK, a citizen of the United States, residing at Springfield, in the county of Hampden and 5 State of Massachusetts, have invented new and useful Improvements in Interrupter Mechanism, of which the following is a specification.

This mechanism relates to an improved 10 interrupter mechanism adapted for use in connection with magnetos and similar devices for interrupting the flow of current through an electric circuit. As an illustration of one of the constructions in connection 15 with which the interrupter may be advantageously employed, reference is made to patent to Brown No. 1,307,343, granted June 24, 1919.

One object of the invention is to provide 20 an interrupter mechanism wherein straight-line movement of the movable breaker point relative to the fixed breaker point is assured, whereby the breaker points are compelled to engage with each other squarely, thus minimizing the effects of arcing and prolonging 25 the useful life of the contact faces.

A further object of the invention is to provide improved means for connecting the 30 movable breaker point with the armature for actuation thereby, through the intermediary of means which compress after engagement of the breaker points and allow overtravel of the armature, thus insuring 35 close engagement of the breaker points even after considerable wear.

Other objects of the invention relate to 40 improved details of construction and arrangement of the parts, as will be more fully set forth in the detailed description to follow.

Referring to the drawings,—

Fig. 1 is a front elevational view of a 45 magneto, a portion of the housing being broken away to show the interrupter mechanism;

Fig. 2 is a side elevational view of the 50 structure shown in Fig. 1, a portion being broken away to show the mountings for the armature and location of the interrupter; and

Fig. 3 is a vertical sectional view of the 55 interrupter mechanism.

Referring to these drawings: the magneto shown is of the general type disclosed in the 55 above-named patent, but other types of

magneton may be employed as desired, the invention being largely independent of the magneto structure. In the magneto shown, 1 designates the housing, which encloses the magnets, coils and other elements except for 60 the lower ends of the cores 2 which project below the housing and are adapted to be periodically connected by an armature 3. As disclosed in the patent above referred to, the cores preferably carry primary and secondary windings, and the interrupter mechanism is adapted to open and close the primary circuit periodically upon reciprocation of the armature.

The armature 3 is lifted by a cam 4 carried by a cam-shaft 5 and engages a roller 6 mounted in the lower end of a vertically-movable sleeve 7 upon which is resiliently supported the armature 3, the springs being concealed within the telescoping housings 7'. The sleeve 7 slides on a fixed guide-rod 8 and a coiled spring 9 surrounds the upper portion of the sleeve 7 and bears against the armature 3 to hold the roller 6 in constant engagement with the periphery of the cam.

A member 10 is provided with an opening 11 formed adjacent one end thereof for the reception of the sleeve 7, and this member is held against the upper surface of the armature by the pressure exerted by the 85 spring 9. Member 10 serves to actuate the interrupter mechanism as will later appear.

The interrupter mechanism is located 90 within the magneto housing and is supported by a member 12, which is of non-magnetic material and connects the lower ends of cores 2. The interrupter mechanism includes a guide cylinder 13, which is suitably fixed in member 12, and supports the fixed breaker point 18. The latter is fixed to a 95 stud 14 which is suitably insulated from the guide cylinder by means of discs 17 of suitable material and held in place by a nut 16. The stud 14 forms one terminal of the 100 interrupter mechanism and is connected by a wire 15 to one terminal of the primary winding, the other terminal of the latter being grounded.

The movable breaker point 20 is fixed to the upper end of a relatively long barrel-like plunger 19 which slides in closely fitting engagement in the guide cylinder 13. The plunger 19 is adapted to be moved by the described member 10, to which it is connected by an actuating rod 21. Rod 21

passes loosely through the lower end of plunger 19 and is provided with a head 22 which loosely fits within the hollow barrel-like part thereof, whereby a limited pivotal or rocking movement of the rod 21 relative to the plunger is permitted. The plunger 19 is supported from rod 21 by a coiled spring 23 located within the plunger and acting between the head 22 and the upper end of plunger 19. Absorbent washers 24 and 25, such as leather or the like, may be positioned within the cylinder 13 and carried by rod 21. These washers are supplied with oil and serve to lubricate the interior of the cylinder during the reciprocation of the plunger. A dust guard 26 is located at the lower end of the cylinder 13 and is provided with a peripheral flange 27 bearing against the lower end of the cylinder, to close the same while the rod 21 freely slides in a passage 28 formed in member 26. A coiled spring 29 surrounding rod 21, bears against the actuating member 10 and the guard 26 to retain the latter in the illustrated position at all times.

It will be seen from the above description that as the armature 3 is raised by the cam 4 into engagement with the cores 2, the member 10 is correspondingly raised to move the plunger 19 upwardly, whereby the breaker points 18 and 20 are brought into engagement and the primary circuit closed. After engagement of these points, the armature may travel a further distance, the spring 23 compressing to take care of the overtravel. This feature is important as insuring firm engagement of the breaker points even after prolonged wear. It would be difficult to make the stroke of the armature and movable breaker point equal and, if made exactly equal, they would soon become unequal because of unequal wear. The straight-line movement of the breaker points is insured by the long and closely fitting guide 19 and the breaker points 18 and 20 are caused to engage squarely entirely across their mating surfaces. This feature is particularly important for it minimizes arcing and the consequent pitting of the points, resulting in prolonged life thereof.

Another important point is that the plunger 19 is not rigidly connected to member 10, but can, as described, rock slightly relatively thereto. The plunger 19 is independently guided in cylinder 13 and the breaker points are therefore self-aligning and not dependent upon an exact alignment of the axes of plunger 19 and sleeve 7.

While the invention illustrated herewith has been described with considerable particularity in order to make clear to those skilled in the art the various structural details which may be employed in a practical utilization of the same, it is to be understood that the invention is not limited to

the practice details of construction illustrated and described, except as they are included in the following claims.

What I claim is—

1. An interrupter mechanism, comprising, 70 a guiding tube, a breaker point supported therein near one end thereof, a cooperating moving breaker point, a plunger in said tube slidably engaged with the interior peripheral wall thereof and by which the 75 movable breaker point is guided in a straight line into square engagement with the first named breaker point, a reciprocable driving member connected to move the plunger by a positive and inelastic transmission of force therefrom in one direction to separate said points, and resilient means through the intermediary of which said driving member moves the plunger in the opposite direction to engage said points, 80 said driving member arranged to continue its travel in the last named direction after the engagement of said points so that it compresses said resilient means, and so that it becomes started on its movement in the 85 first named direction and acquires momentum before it moves said plunger by said inelastic transmission of force to separate said points.

2. An interrupter mechanism, comprising, 95 a guiding tube, a fixed breaker point supported therein near one end thereof, a relatively long plunger slidably mounted in said guide tube, and carrying a mating breaker point, a driving member connected with said plunger capable of slight pivotal movement relative thereto, and resilient means interposed between the said member and one end of the plunger.

3. An interrupter mechanism, comprising, 105 a hollow guiding sleeve closed at one end, a breaker point within the sleeve and fixed in the closed end thereof, a plunger closely fitting said sleeve and slidably therein, a mating breaker point carried by said plunger, driving means for the plunger extending through the open end of said sleeve, and a closure member loosely mounted on the driving means and closing the open end of the sleeve.

4. An interrupter mechanism, comprising, 110 a hollow guiding sleeve closed at one end, a breaker point within the sleeve and fixed in the closed end thereof, a plunger closely fitting said sleeve and slidably therein, a 115 mating breaker point carried by said plunger, driving means for the plunger extending through the open end of said sleeve, and a closure member loosely mounted on the driving means and closing the open end of the sleeve, an abutment on the driving means outside said sleeve, and a spring acting between said abutment and the closure member to hold the latter against the sleeve at all 125 times.

5. An interrupter mechanism, comprising, a hollow guiding sleeve closed at one end, a breaker point within the sleeve and fixed in the closed end thereof, a hollow plunger slidable therein and closed at both ends, a mating breaker point carried by one closed end of the plunger, driving means for the

plunger extending through the other closed end of the plunger and having a head to engage such end, and a spring between the 10 head and the first-named end of the plunger.

In testimony whereof I have affixed my signature.

HAROLD H. CLARK.
